UNITED STATES PATENT OFFICE.

CARL EMIL EHN BORN, OF LONG ISLAND CITY, NEW YORK.

MEANS FOR MOUNTING THE GRIP ON CABLE-RAILWAY CARS.

SPECIFICATION forming part of Letters Patent No. 398,590, dated February 26, 1889.

Application filed September 11, 1888. Serial No. 285,142. (No model.)

To all whom it may concern:

Be it known that I, CARL EMIL EHN BORN, a citizen of the United States, residing at Long Island City, in the county of Queens and State 5 of New York, have invented a new and useful Improvement in Cable-Railway Cars, of which the following is a specification.

My invention relates to mechanism whereby the grip-gear attached to a cable-railway car may be transferred from the terminal of one cable to that of another, and may also be passed around curves at places along the track where switches and curves occur. One common expedient for this purpose is to secure the grip-gear to sliding bars extending crosswise of the car-truck, and which are moved laterally by means of the cable-conduit slot, which is led at the switch-point considerably from the center of the track. By 15 this arrangement the sliding bars in switching a car project beyond the sides thereof, whereby accidents and other undesirable results are liable to take place.

My invention consists in securing the grip-gear to sleeves mounted to slide on stationary bars attached to the framing of the truck, whereby said undesirable results are avoided, and whereby comparatively little space is required for the lateral movement of the grip-gear when moved sidewise, corresponding to 30 the deviation of the conduit-slot from the center of the track, and more available space is obtained for the brake and other mechanism pertaining to a cable-car truck.

In the accompanying drawings, Figure 1 is a plan of a truck-frame having my improvement applied thereto. Fig. 2 is a transverse section thereof, taken on the line *x* *x*. Fig. 3 is a side elevation of a portion of the grip-actuating mechanism. Fig. 4 is a detached view of the sleeve. Fig. 5 is a plan illustrating a modification.

Similar letters of reference indicate corresponding parts.

45 A designates a truck, which may be of any ordinary suitable construction and having a car mounted thereon in the usual manner. As here shown, the truck consists of side beams, B B', cross-bars C C', and intermediate bars, D D', firmly secured together.

E E' are metallic bars secured to the bars D D' by means of keepers F, bolted to the said bars D D', and having split or other suitable pins, d, inserted at their extremities.

55 G G' are sleeves of suitable material loosely

mounted to slide on the plates E E'. These sleeves have cast integral therewith or otherwise rigidly affixed thereto posts g g', to which is pivotally connected the head-block H. On this head-block the grip-gear, of usual construction, is carried. As here shown, it consists of two bars, h h', rigidly secured thereto and extending down through the slot of the cable-conduit, and having suitable gripping mechanism attached thereto.

h² is a lever fulcrumed at h³ and rocked thereon by suitable mechanism within the car through the rod h⁴.

I is an arm pivoted to the bars J J', and having an adjustable bearing-block, i, pivotally connected to the lever h². On reciprocating the rod h⁴ a downward-and-upward movement is imparted to the bars J J', operating to grip or release the cable.

In Fig. 5 the sleeves G G' are shown provided with pockets g² g³, cast integral therewith, into which the ends of the head-block H are fitted.

By my improvement a new sleeve, in case of breakage, may be readily substituted by withdrawing the bar E or E' from its keepers sufficiently for the purpose.

Having now described my invention, what I claim as new, and desire to secure by Letters Patent, is—

1. In a cable-railway car, the combination of stationary bars extending crosswise of the track-frame and detachably secured to the same, with sleeves loosely mounted to slide on said stationary bars, each sleeve consisting of a block having an opening extending centrally through it adapted to receive one of the said stationary bars, and also having an end portion of the grip-carrying head-block pivotally connected thereto, substantially as described.

2. In a cable-railway car, the combination, with the car-truck, of stationary bars extending crosswise of the car and passing loosely through keepers secured to the truck-frame, and held in place by pins passing through their extremities, and sleeves loosely mounted to slide on said stationary bars and having pivotally connected thereto the head-block carrying the grip-gear, substantially as described.

CARL EMIL EHN BORN.

Witnesses:
JOHN HART,
GEO. WADMAN.

It is hereby certified that the name of the patentee in Letters Patent No. 398,590, granted February 26, 1889, for an improvement in "Means for Mounting the Grips on Cable-Railway Cars," was erroneously written and printed "Carl Emil Ehnborn," whereas said name should have been written and printed *Carl Emil Ehnbom*; and that said Letters Patent should be read with this correction therein that the same may conform to the record of the case in the Patent Office.

Signed, countersigned, and sealed this 12th day of March, A. D. 1889.

[SEAL.]

D. L. HAWKINS,
Assistant Secretary of the Interior.

Countersigned:

BENTON J. HALL,

Commissioner of Patents.
